US00D600127S

(12) **United States Design Patent**
Kuzma et al.

(10) **Patent No.:** US D600,127 S
(45) **Date of Patent:** ** Sep. 15, 2009

(54) **BOTTLE**

(75) Inventors: **Gene J. Kuzma**, Powell, OH (US);
Elizabeth T. Tkacheff, Columbus, OH
(US)

(73) Assignee: **G.K. Packaging, Inc.**, Plain City, OH
(US)

(**) Term: **14 Years**

(21) Appl. No.: **29/297,714**

(22) Filed: **Nov. 16, 2007**

(51) **LOC (9) Cl.** 09-01

(52) **U.S. Cl.** D9/530; D9/563; D9/574

(58) **Field of Classification Search** D9/434,
D9/435, 452, 453, 516, 529, 530, 537-539,
D9/541-543, 559, 560, 563, 566, 567, 571-575;
215/382-384; 220/669-675

See application file for complete search history.

Assistant Examiner—Keli L Hill

(74) *Attorney, Agent, or Firm*—Michael J. Gallagher; David J. Dawsey; Gallagher & Dawsey Co. L.P.A.

(57) **CLAIM**

The ornamental design for a bottle, as shown and described.

DESCRIPTION

FIG. 1 is a front elevation, the rear elevation being identical.

FIG. 2 is an elevation of the left side, the right elevation being identical.

FIG. 3 is a perspective view of the front and right side, the rear and left side perspective being identical; and,

FIG. 4 is a top plan view.

The broken-line disclosure in the views is for illustrative purposes only and forms no part of the claimed design.

1 Claim, 2 Drawing Sheets
